UNITED STATES PATENT OFFICE.

CHARLES H. DAVIDS, OF BROOKLYN, ASSIGNOR TO HIMSELF, AND DAVID F. DAVIDS AND MAY DOW DAVIDS, OF NEW ROCHELLE, NEW YORK.

MACHINE FOR MAKING STEREOTYPE-MATRICES.

SPECIFICATION forming part of Letters Patent No. 274,918, dated April 3, 1883.

Application filed October 4, 1881. (No model.)

To all whom it may concern:

Be it known that I, CHARLES HENRY DAVIDS, a citizen of the United States, residing at Brooklyn, in the county of Kings and State of New York, have invented an Improvement in Typography, of which the following is a specification.

I produce slight but sharply-defined impressions from clearly-cut types into lead or analogous soft metal. I can use such soft metal thus impressed with sunken characters by inking, wiping, and printing for what is known as "plate-printing," but for ordinary printing my plates simply serve as matrices, from which to produce relief-plates by electrotyping or analogous means. With these relief-plates surface-printing may be performed, as will be obvious.

I will describe the invention as employed for the production of small plates, each adapted to serve as a matrix for a portion of one column of newspaper matter. I find that a useful effect can be produced by impressing the characters to a very small depth, using lead as the matrix. After getting a very thin coating of oxide on the surface, by a sufficient exposure to the air or otherwise, I can use my plate as a mold from which to cast the reverse plates in ordinary type metal, or, preferably, in a more fusible metal. I make the matrix or mold-plate to receive the impressions by facing a rigid back piece with soft metal, joined by fusion. It may be formed by soldering a facing of sheet-lead on the back piece; but, if cast thereon, it must be smoothly faced, either in the act of casting or by a subsequent treatment, so as to leave an even surface before the types are impressed.

A separate application will be made for Letters Patent for the process thus far described for producing printing-plates or matrices therefor, this application referring only to the machine used in connection therewith, as herein-after specified.

I mount the mold-plate in a holder capable of being moved for the spacing, and impress the types successively therein by a series of punches held in a wheel in a position parallel to the axis and capable of being moved endwise. The wheel is rotated by suitable mechanism, which allows it to be stopped without stopping the whole machine, and is arrested

in the right position at the will of the operator by striking one of a series of keys, which brings the proper stop into contact with a spur or projection on the wheel at a required point in its circuit. The mechanism forbids any recoil of the punch-wheel on its being arrested. I provide for withholding the impressions until the type-wheel or punch-wheel is stopped, and then produce the impression by a further movement of the same key. I arrange the locking-levers in one-half instead of the whole of the circle, and arrange them in two or more tiers, acting on a corresponding number of flanges, fixed on the punch-wheel. The depression and subsequent liberation and elevation of the proper key effects, first, the stopping of the wheel with the desired type or punch in position, then the impressing of that punch and its withdrawal, then the unlocking and allowing the wheel again to commence its active rotation, and, lastly, and, to a certain extent, simultaneously with the unlocking, &c., the feeding or moving of the mold-plate which receives the impression, this latter being to a greater or less distance, according to the width of the particular letter which has just been impressed. I provide an excess of force for each impression; and employ a firmly-supported stop close to the impression - surface to receive the excess of force and insure that all the letters are impressed to an exactly uniform depth. Adequate provision is made for varying the spacing to "justify," or make the lines all of equal length. I so operate the machine that all irregularities in the spacing, should any occur, are near the middle of each line, as in ordinary typography, where it but slightly affects the appearance of the print. I also provide for conveniently varying the distance of the several letters apart in the whole or a part of the words to facilitate justification. After the completion of each line the receptive mold-plate is shifted in position to the proper extent to receive the next line of impressions; and I provide facilities for giving more or less space between the lines in fine degrees of gradation. There are key-levers for designating the types or punches to be impressed in their proper order. These are also connected with the feeding mechanism, so that their operation effects a proper amount of feed for

each letter. There is another set or series of key-levers for effecting the spacing between the words. These serve by feeding the mold-plate along to a greater or less extent, according to which of the series is operated; and there is still a third set or series of key-levers for line-spacing. They move the mold-plate, when each line is finished, in the proper direction to prepare for the next line. The extent of the space thus induced between the lines is greater or less, according as one or another key of the series is operated. All these several series of key-levers may lie side by side in an apparently continuous line, the keys, which extend up therefrom and are provided with suitable buttons to receive the touch of the fingers, being arranged in several rows or banks. The parts are so represented.

The following is a description of what I consider the best means of carrying out the invention:

The accompanying drawings form a part of this specification.

Figure 1 is a front view of the entire machine, partly in section. Fig. 2 is a plan view, with a portion broken away to show the parts below. Fig. 3 is a side elevation. The succeeding figures are on a larger scale. Fig. 4 is a vertical section, showing certain portions. It is a section through the center of the punch-wheel in a plane extending forward and back. Fig. 5 is a front elevation of certain parts, partly in section. Fig. 6 is a front elevation, showing certain parts. Fig. 7 is a side elevation, showing certain parts. Figs. 8, 9, 10 are on a still larger scale. Fig. 8 represents the spacing-clutch and its connections, partly in section. Fig. 9 is a cross-section on the line S S looking in the direction of the arrows. Fig. 10 is a section on the line T T in Fig. 8 looking in the direction of the arrows.

Similar reference-letters or pairs of letters indicate like parts in all the figures.

For the mold-plate *m p*, I take a block or plate, of brass or other hard metal, of sufficient thickness, and carefully tin the face thereof. I place this in a mold, and on the tinned face apply melted lead, tin, or zinc, or a suitable soft-metal alloy. If it is not practicable to mold this with a sufficiently-smooth face I cast it with an excess of thickness, and then place this compound block in a machine analogous to a stereotype-planer and shave the soft face and polish to a perfectly even surface and trim the edges. On the soft metal, thus supported by being fused on an unyielding back, I punch the desired characters.

The punch-wheel *T w* revolves on a stud, 7, fixed on a bridge-piece, 9, of the frame, and has locking-flanges *l f* on its periphery. This punch-wheel *T w* carries a number of movable supports or puppets, *p*, one for each character to be used in the machine, and which slide freely lengthwise in upright mortises cut in equal divisions of the punch-wheel near its periphery. Each of the puppets *p* carries in its up-

per end a type-punch, *t p*. Near its lower end is a recess, *a'*, in one edge, leaving a lip, *a*. Each type-punch is fixed in its puppet by a set-screw, *b*, which also acts as a stop, preventing the puppet from dropping below the desired point.

A miter-wheel, *g*, is formed or secured on the hub of the punch-wheel *T w*, and gears into a similar wheel, *g'*, on a horizontal shaft, *r*, revolving in fixed bearings.

Power is received by a belt from a line-shaft. (Not shown.) The belt runs on a pulley, *P*, fixed on a sleeve, *s l*. A friction-plate, *f*, slides on the sleeve *s l*, but is prevented from turning thereon by the spline *d*. Between the friction-plate *f* and the adjacent surface, which is the side of the pulley *P*, a washer, *w*, of felt or other frictional material, is compressed by the nut *N* on a screw-thread formed on the sleeve *s l*.

A shaft, *l*, extending across the rear of the machine, rests in bearings in standards 2, and is the fulcrum for a series of key-levers, *K l*, *K t*, and *K s*, lying side by side, like piano-keys, 90 having finger-buttons attached. The weight of each key-lever is a little more than balanced by a spring, *3*, attached to its rear end and to the base-plate *B*. The front ends of these levers move freely in the guideways formed in a stop-bar, *S b*, at the front of the machine, which arrests the descent of the key-levers when depressed to the proper line.

The levers *K t*, which may be called "type-levers," are equal in number to the letters, figures, and other characters used in the machine, and serve one for each. To aid learners in operating, each finger-button may have one of said characters conspicuously exhibited. Each lever *K t* is connected by a link, *4*, with one of the locking-levers *l l*, which, equal in number to the levers *K t*, are arranged in two ranks in semicircles on the grooved locking-plate *l p*. The outer ends of the locking-levers *l l* are held up by elbow-springs *6*. The inner ends 110 stand under the locking-flanges *l f*, one for each rank of levers, on the periphery of the punch-wheel *T w*.

Each locking-flange *l f* has one narrow score or slot, *s*, cut through it. Immediately adjacent, on the proper side, is an arresting-spur, *8*, which projects from the flange. These slots *s* and spurs *8* bear such a relation to each other and to the locking-levers *l l* that the latter, by engaging in the former, will lock the punch-wheel *T w* in a different position, according as one or the other key-lever *K t* is depressed.

A clutch-plate, *e*, on the end of the sleeve *s l*, engages with a clutch-plate, *e'*, on the shaft *r*. The hub of the plate *e'* is notched, preferably, in one full turn of a spiral, and engages with a collar, *C²*, having a like formation on its face. A spiral spring, *h*, encircling the shaft *r*, has one end attached to the notched collar *C²*, and the other end to a collar, *i*, secured to the shaft *r*. The clutch-plate *e'* has a circumferential groove in its hub, and in this groove a yoke,

5 *y*, engages, which is hinged at one end to the frame-work of the machine, and at its other end to a link, *j*, connecting with one arm of a bell-crank lever, *k*. The other arm of the lever *k* is connected by a link, *j'*, with a lever, *m*, operated by the working of the toggle 12 13.

10 The receiving-power pulley *P* being revolved, the nut *N* is screwed up on the sleeve *s l* until the friction-plate *f* compresses the elastic washer *w* sufficiently. The collar *i* on the shaft *r* is adjusted so that the spring *h* will hold the clutch-plate *e'* against the clutch-plate *e*. The shaft *r*, with its miter bevel-wheel *g'*, being thus made to revolve, turns the punch-wheel or 15 type-wheel *T w*. The lever *m*, being depressed, opens the clutch *e e'* by operating the link *j'*, bell-crank lever *k*, link *j*, and yoke *y*, and the punch-wheel *T w* stops.

20 It will be seen that depression of a type-key lever, *K t*, raises the inner end of its connected locking-lever *l l* against the proper locking-flange *l f*, which nevertheless continues to revolve freely until its spur or detent 8 strikes the said elevated locking-lever *l l*. Then the 25 locking-lever, continuing to be pressed gently upward by the continued pressure of the finger on the proper key-lever, passes into the slot *s*, permitting a still further depression of the key-lever *K t*, which then moves quite to 30 the bottom of its groove or guideway in the stop-bar *S b*. When pressure ceases on the key-lever *K t* the locking-lever *l l* returns, leaving the punch-wheel *T w* free to revolve, and the clutch *e e'* is closed. The notched collar *C²* on the end of the spring *h*, in connection 35 with the notched end *e²* of the hub of the clutch-plate *e'*, acts as a click or ratchet to prevent the machine from revolving in the wrong direction. Should the punch-wheel *T w* be 40 stopped, and the clutch *e e'* not be opened soon thereafter, the friction device *P w f* will permit the pulley *P* to revolve without injury to the machine.

45 On the shaft 1 is mounted the impression-lever *I l*, formed as a broad frame, extending across beneath all the type-levers *K t*. Adjusting-screws *o o* are set in its front part, one under each type-lever *K t*. On its upper surface it carries a forked standard, 10, passing 50 between the levers *K t* and connected by an adjustable link, 11, with a bell-crank lever, 12, which, with the link 13, forms a toggle or knee joint. The link 13 is also jointed to the slider 14, the upper part of which has a recess, *a²*, 55 and a lip, *a'*, to correspond with the like formation of the lower ends of the type-puppets *p*. The slider 14 moves in the slide-plate 15, which is secured to the bridge-piece 9 of the frame of the machine. The bell-crank lever 12 is attached to the rock-shaft 16, which rocks in the journal-boxes 17 17, and which carries on its end the lever *m*, before mentioned. A stop screw or pin, 18, in the slider 14, moving in a slot in the slide-plate 15, acts as a stop on the 60 slider 14, permitting its descent only to the point where it will engage with the puppets *p*.

A spring, *n*, raises the impression-lever after it has been depressed.

70 A positive stop, *P s*, attached at one end to the stud 7, is extended outward across the path of the type-punches *t p* and firmly bolted to the fixed framing. Through a sufficient hole in this stop the type-punches *t p* are successively thrust as the several impressions are produced; but the ends of the puppets *p* are received by the stop *P s*, and thus regulate the impression. 75

80 On the posts 30 I place on each side of the frame-plate *f p* adjusting-nuts 31 32, two on each of the four posts 30, one of each pair 31 being below and the other, 32, above the frame-plate *f p*. These serve to adjust the distance of the mold-plate *m p* from the type-punches *t p* when the thickness of the mold-plate is subject to considerable variation. 85

85 The ends of the adjusting-screws *o o* in the impression-lever *I l* are at such a distance below the type-levers *K t* that the latter, when operated, do not touch them until the type-wheel *T w* is locked. They are arranged to 90 compensate for the springing of the impression-lever *I l*, and for the difference in the pressure required by the various type-punches *t p*. One of the type-levers *K t* being depressed a little raises the corresponding locking-lever *l l* into contact with its proper locking-flange *l f*, and then is compelled to wait until the punch-wheel *T w* is arrested, and the slot *s* receives the locking-lever *l l*. Then the key-lever *K t* is allowed to sink lower, and depresses in turn the impression-lever *I l*. This, by the thin forked standard 10, playing through sufficient spaces between the key-levers, draws down the link 11, and, by the action of the toggle-joint 12 13, pushes up the slider 14. The 95 several parts must be so arranged and proportioned that on the stoppage of the punch-wheel the puppet required has been presented in line above the slider and engaged therewith by means of its lip *a*. The slider 14 rises, 100 carrying the engaged puppet *p* and its type-punch *t p*, and forces the latter into the soft surface of the mold-plate *m p* until the puppet *p* is arrested by the stop *P s*. On the return motion of the slider 14 its lip *a²* retracts the 105 puppet *p* until both are stopped, the slider 14 by the stop-pin 18, and the puppet *p* by the set-screw *b*, and all is ready for the revolution of the punch-wheel *T w* to be again resumed. 110

115 On the shaft 1 swings a broad lever, *S l*, 120 nearly similar in form and dimensions to the impression-lever *I l*. This lever is for spacing or feeding along the mold-plate to an extent corresponding to the width of each letter imprinted. It extends under the type-levers *K t*, 125 and is operated by each to just the proper extent for its letter. It also extends under a set of additional levers, *K s*, which latter are depressed by the operator when required for blank spacing between the words in place of 130 the quadrats and spaces used by compositors.

130 The front of the lever *S l* carries adjusting-

screws q q , which are set to engage under the levers K t and K s one screw q for each lever K t or K s . The height of these screws q q is adjusted in the lever S l according to the width 5 of the face of the corresponding type represented by the key-lever over it. In the case of the levers K s the adjustment is in proportion to the amount of blank space to be thereby provided.

10 The spacing-lever S l , after it has been depressed and released, is raised by a suitable spring. It is connected by an adjustable link, 19, with a ratchet-lever, R l , which carries a series of ratchets, R R , of different lengths, 15 operating the ratchet-wheel R w on the spacing-shaft 20. On this latter are two bevel-pinion, 21 21, gearing into corresponding bevel-wheels 22 22, lying at right angles thereto, which latter are on spindles 23 23, on which 20 are friction-clutches t t , fastened and released by the turning of knobs u u . They carry wheels x x , which, when engaged by their respective friction-clutches, tend to turn in opposite directions. These wheels x x carry a belt 25 or band, V , preferably of metal, having projections on its inner face engaging with transverse grooves on the faces of the friction-wheels x x . This belt is attached to the spacing-carriage S c , which slides on the under side 30 of the frame-plate f p in guides z z . A turn-buckle, 33, serves to keep a suitable tension on the spacing-belt V to prevent loss of motion by looseness thereof.

35 The ascent of the adjustable link 19, when the spacing-lever S l has been depressed and is allowed to rise again, is delayed by a looseness of the connections represented in Fig. 3, so that the spacing mechanism will not begin to act until sufficient time has elapsed to allow 40 the type-punch t p to leave the mold-plate m p . So, also, the several parts must be so adjusted that the proper locking-lever l l will retain its hold on the punch-wheel T w until the puppet, with its punch, has been drawn completely 45 down.

45 Each friction-clutch t (see Fig. 8) has a circular plate, t' , fixed on the sleeve t^1 , to which the gear-wheel 22 is keyed, and a similar circular plate, t^2 , fixed on a sleeve, t^2 , in line with 50 the first. Within these sleeves is a stem, 23, which extends also through the wheel x . The end of this stem is screw-threaded, and receives a hand-wheel or nut, u , which is threaded differentially—that is to say, on the end of the 55 stem 23 is a screw tapped through the nut, and on the sleeve t^2 is a screw-thread of different pitch, also engaging with the nut u . Each clutch revolves in journal-boxes attached to the frame-plate f p . The screw-threads act 60 differentially in opening or closing the plates t' and t^2 against the wheel x by means of the nut u . I propose to apply for a separate patent for a clutch constructed with differential screws, as herein described and shown.

65 One of the key-levers K t or K s , being depressed at the proper point in its descent,

strikes an adjusting-screw, q , and depresses the spacing-lever S l , thus allowing the link 19 to fall and the ratchet-lever R l and ratchet R to draw back for a fresh hold. On the key 70 being released these parts return to their former positions by the force of the springs n' and 3 , and in doing so one of the pawls R , which has engaged with the ratchet-wheel R w , turns it a distance proportionate to the extent to which the spacing-lever S l has been depressed. The ratchet-wheel R w turns the shaft 20, and necessarily, also, the beveled pinion 21 and wheel 22, with the attached sleeves t^1 t^2 and plates t' t^2 , each pair in an opposite 80 direction. One of the clutches being disengaged and the other engaged, the latter will at each reciprocation of the link 19 feed forward the mold-plate m p to a distance corresponding to the breadth of the letter which has just 85 been impressed. Should the left-hand clutch be brought into operation, by screwing up the left-hand nut u , the carriage S c will move from right to left; but should the left-hand nut be released and the other nut be tightened, 90 the motion of the carriage will be reversed.

Two adjustable stops, 34 34, are attached to the frame-plate f p to aid in setting the spacing-carriage S c at each end of a line, and thus determine the width of the column or page. 95 When a certain portion of the line—say from one-half to two-thirds—has been impressed, by beginning at the commencement of the line, in the usual way, the forward-clutch then in operation, which is the left-hand one, is released by turning the hand-wheel or nut u at the left. The spacing-carriage S c is next pushed by the hand of the operator quite over against the stop 34 at the last end of the line. Then the reversing-clutch on the right is engaged, and the remainder of the line is set up 105 backward. This allows the ends of the line to be exactly even. Wider or narrower spaces are made between the several words by playing different spacing-keys K s . Wider or narrower spacing of the entire set of characters 110 may be obtained by shifting the point of connection of the link 19 moving in the slot 28 in the spacing-lever S l .

115 The proper spacing between each line and the next is secured as follows: On the shaft 1 swings a line-spacing lever, L l , which is operated by the key-levers K l , and extends across and beneath them. L l is connected by a link, 24, with a ratchet-lever, r l , carrying several ratchets r' , which operate the ratchet-wheel r w , attached to the line-spacing shaft l s , on which is the spur-wheel S w , engaging in the rack r k , which abuts against the mold-plate m p , sliding between guides x' x' on the spacing-carriage S c . Adjustments 27 27 are provided in the stop-bar S b for the line-spacing key-levers K l . They may be small blocks of different lengths, as shown, or adjusting-screws, as may be deemed best. A spring, 25, raises the lever L l after it has been depressed. A lifter, 26, lifts the ratchet r' from the ratchet-

wheel, permitting the rack $r k$ to be returned to its starting-point.

An additional key-lever, m' , (see Fig. 5,) is connected to the link j' , to disengage the clutch $e e'$ at will independently of the impression mechanism. I can use it either for the purpose of stopping the punch-wheel for examination or for any purpose while the belt is still connected, or by using it, in combination with any given key-lever $K t$, to obtain consecutive impressions of one type-punch with a proper feed between each impression without waiting for the type-wheel to revolve for each. This may be especially useful in repeating the cipher in figure-work, involving large quantities.

Operation: The spacing-carriage being against the proper stop in the position for commencing a line, and the letter-spacing device properly adjusted, the operator puts a mold-plate, $m p$, in the guides $x' x'$, places copy before him, and connects the belt P' to set the type-wheel $T w$ revolving, and closes the spacing-clutch t , which moves the spacing-carriage $S c$ forward. He then depresses the lever $K s$, that represents an em-quadrat, once or oftener, as may be necessary. He then consecutively depresses different type-levers $K t$ until the first word is formed. He then depresses a key-lever, $K s$, which represents an ordinary space between words, and then consecutively depresses levers $K t$ to form the next word. At a suitable point, before the line is completed, he opens and disengages the left clutch, t , which had been operative, moves the spacing-carriage $S c$, with the mold-plate $m p$, against the opposite stop, and, having, by a quick mental process determined what word or part of a word will come at the end of the line, proceeds to impress in a reversed order as much matter as will be necessary to fill out the line, spacing it more or less, as required. Having finished the line, he opens the reverse clutch t , and, applying his hand, moves the spacing-carriage $S c$, with the mold-plate $m p$, to the other stop, 34, and closes the forwarding-clutch. Then, to put the plate in position for the next line, he depresses the proper lever $K l$, thus moving the mold-plate $m p$ forward more or less, according to which lever is so depressed, and, commencing a new line, repeats the operation previously described until the plate is filled or the copy is all composed. Should the operator discover an error before beginning the next line, he composes a corrected line beneath the incorrect one, and continues as before, leaving the incorrect line to be cut out of the casting or electrotype taken off of the mold-plate. It is hardly necessary to say that, should errors be discovered after succeeding matter has been correctly composed, all the incorrect matter can be cut out of the casting or electrotype taken therefrom, and correct matter can be inserted in its place. In like manner authors' corrections of text may be made.

It is preferable to have the mold-plate contain but a small quantity of matter, so that in-

accuracies will never cause more than a few moments lost time.

Nearly all the errors in ordinary type-setting arise from "foul" cases—*i. e.*, compartments in the type-cases containing types not belonging therein. The work of a machine of this class is free from such errors.

Modifications may be made in many of the details. Parts of the invention may be used without the whole.

I do not confine the invention to the employment of levers of the kind shown for the devices $l l$. I can use therefor other kinds of levers or devices, which are levers of any kind—*as, for example, slides.* It is sufficient if they are employed in a series and serve as described relative to the key-levers and to the flange or flanges $l f$.

The punches used may be matrix-formed—*i. e.*, have the desired characters impressed in them, and thus produce a relief-plate by operating the machine, as described.

I propose to make a separate application for patent for the process of manufacturing printing-plates by forming a matrix by consecutive impressions of types into metal and then taking a casting therefrom.

Should it be desirable to cast a stereotype-plate of type-metal, or any other alloy which requires comparatively high heat to fuse, I cover my rigid plate m with clay or other suitable refractory substance, kneaded with glycerine in proper proportions, instead of the soft metal fused on, as above described. The soft earthy coat, of proper consistency, thus provided will remain in good condition a long time to receive impressions, and serve at any required period afterward as the mold, from which a sharp casting in the proper metal can be taken. This will be made the subject of a separate application for patent.

The mold-plate $m p$, or a sufficiently-hard reproduction made therefrom, can be used to produce a relief-plate by other means than stereotyping or electrotyping. It may be used by mechanically pressing it upon a suitable yielding surface. The material and thickness may vary according to the purpose for which it is intended to be used. It may be made cylindrical or segmental, proper modifications being made in the holder and in the means for moving it.

Although I have termed this invention an "improvement in typography," for which I have described it as being used, the same mechanism may be used with or without modifications for the impressing of other devices than printer's types, and for other purposes than printing. I can, for example, provide punches adapted to impress scrolls or other decorative devices, or parts of such devices, and use this machine to combine them in a great variety of relations on a properly-grooved mold-plate, which mold-plate may, if desired, be afterward used as a matrix from which to produce dies for use in embossing, chasing, and decorating.

paper, leather, woven fabrics, &c., for a great variety of purposes.

I claim as new and as my invention—

1. The combination of the key-levers $K t$, 5 impression-lever $I l$, link 11, toggle-joint 12 13, slider 14, puppets p , and type-punches $t p$, arranged substantially as and for the purpose set forth.

2. The key-levers $K t$ and impression-lever $I l$, with an adjusting device, 11, and train of connections to the type-punch $t p$, substantially as shown.

3. The key-levers $K t$, impression-lever $I l$, and its adjustments $o o$, in combination with 15 a train of connections to the type-punch $t p$, substantially as shown and described.

4. The combination of the key-levers $K t$, the impression-lever $I l$, the connections from the impression-lever $I l$, and including the 20 slider 14 and the return-stop 18, arranged substantially as and for the purpose specified.

5. A punch-wheel and its rotating mechanism, in combination with the locking-levers $l l$, and with a cushioning-spring, h , the latter interposed between the driving mechanism and the punch-wheel, substantially as and for the purpose set forth.

6. The device h , C^2 , and c^2 for preventing the communication to the punch-wheel of a 30 reversed motion of the rotating mechanism, and in combination with said punch-wheel and rotating mechanism, substantially as specified.

7. In combination with each other and with the mechanism for rotating a carrier containing 35 a set of punches, a continuously-operative friction-clutch, and a positive clutch, ee' , which is disengaged while a punch is being impressed, substantially as and for the purpose specified.

8. The friction-plate f and means for adjusting it, compressible washer w , and pulley or driving-wheel P , in combination with a punch-wheel and mechanism for revolving the same, substantially as set forth.

9. A series of key-levers, $K t$, and their connections, in combination with the punch-wheel $T w$, with one or more flanges, $l f$, thereon, whereby the type key-levers, after a partial movement, are detained until the punch-wheel is stopped, substantially as herein described and shown.

10. A punch-wheel provided with detaining-flange $l f$, having a releasing-slot, s , in combination with the key-levers $K t$ and connected mechanism, as herein specified.

11. A punch-wheel provided with detaining-flange $l f$, in combination with its rotating mechanism and with the key-levers and their connections, arranged, substantially as shown, so as to prevent the simultaneous operation of 60 two or more of the latter.

12. A series of locking devices adjacent to and arranged around a punch-carrier, the latter furnished with a slotted flange, into which the locking devices may engage singly to prevent motion in the punch-carrier, substantially as shown.

13. The punch-wheel $T w$, having a slotted detaining-flange, $l f$, and spur 8 , in combination with the locking-levers $l l$, the latter arranged to perform the double function of stopping the punch-wheel and locking it to prevent motion thereof in either direction, substantially as set forth.

14. A punch-wheel having a detaining-flange, $l f$, furnished with a slot, s , and spur 8 , in combination with checking devices, substantially as shown.

15. The grooved locking-plate $l p$, formed substantially as described, and a series of locking devices pivoted therein, in combination with a spur and slotted detaining-flange on a punch-carrier, substantially as shown.

16. The key-levers $K t$ and suitable connections, substantially as described, to a series of 85 locking mechanisms, substantially as described, in combination with each other and with a detaining-flange, $l f$, on a punch wheel or carrier, substantially as set forth.

17. In a machine for impressing types successively, the combination of a friction-wheel, x , friction-plate, t^2 , and means, substantially as described, for engaging them at will with a spacing-carriage and letter-spacing mechanism, and devices connecting them to the friction-wheel x , all substantially as described.

18. A mold-plate and spacing-carriage, in combination with reversible spacing mechanism.

In testimony whereof I have hereunto set my hand at New York city, this 1st day of October, 1881, in the presence of two subscribing witnesses.

CHARLES H. DAVIDS.
